UNITED STATES PATENT OFFICE.

JOHN F. MEIGS, OF SOUTH BETHLEHEM, AND WILLIAM W. JOHNSTON, OF BETHLEHEM, PENNSYLVANIA, ASSIGNORS TO BETHLEHEM STEEL COMPANY, OF SOUTH BETHLEHEM, PENNSYLVANIA, A CORPORATION OF PENNSYLVANIA.

DESIGN FOR A SADDLETREE.

SPECIFICATION forming part of Design No. 35,328, dated November 26, 1901.

Application filed October 12, 1901. Serial No. 78,502. Term of patent 14 years.

To all whom it may concern:

Be it known that we, JOHN F. MEIGS, residing at South Bethlehem, and WILLIAM W. JOHNSTON, residing at Bethlehem, in the county of Northampton and State of Pennsylvania, citizens of the United States, have invented and produced a new and original Design for a Saddletree, of which the following is a specification, reference being had to the accompanying drawing, forming part thereof.

The figure is a perspective view of a saddletree, showing our new design for a tree.

As shown in the drawing, the leading or material feature of our design for a saddletree shaped to fit a pack-animal consists of a skeleton frame having arched ribs C and cross-pieces D', disposed or arranged in relation to each other, as shown in the drawing, with openings O between the ribs and cross-pieces. The ribs and cross-pieces are provided with flanges a and c, arranged as disclosed in the drawing and of substantially the configuration shown, while the frame has ears B, with

hollowed tops, arranged thereon in the position shown, said ears also having flanges arranged around the edges of the same. Extending from the frame are horns E, of the shape disclosed, and arranged with reference to the parts of the device as shown in the drawing, while other flanges F are arranged upon the frame in the position set forth in the drawing.

Having described our invention, what we claim, and desire to secure by Letters Patent, is—

The design for a saddletree as herein shown and described.

In testimony whereof we have signed our names to this specification in the presence of two subscribing witnesses.

JOHN F. MEIGS,
WILLIAM W. JOHNSTON.
